UNITED STATES PATENT OFFICE.

WILLIAM G. WINTER AND HERBERT I. FINCH, OF ST. LOUIS, MISSOURI, ASSIGNEES
TO THE EMERSON ELECTRIC MANUFACTURING COMPANY, OF ST. LOUIS, MISSOURI,
A CORPORATION OF MISSOURI.

OSCILLATING MECHANISM FOR ELECTRIC FANS.

1,347,981.

Specification of Letters Patent. Patented July 27, 1920.

Application filed May 7, 1919. Serial No. 295,341.

To all whom it may concern:

Be it known that we, WILLIAM G. WINTER and HERBERT I. FINCH, citizens of the United States, residing at the city of St. Louis, 5 State of Missouri, have invented a certain new and useful Improvement in Oscillating Mechanism for Electric Fans, of which the following is a full, clear, and exact description, such as will enable others skilled in the 10 art to which it appertains to make and use the same.

This invention relates to a certain new and useful improvement in oscillating mechanism for electric fans, and particularly to the 15 means for adjusting said oscillating mechanism, being designed particularly as an improvement upon United States Letters Patent No. 1,256,121, granted to Herbert I. Finch and Thomas M. Meston under date of 20 February 12, 1918.

In this invention the oscillatory movement of the fan may be varied or eliminated, as desired, and said adjustment can be made while the fan is in operation or stationary. 25 The principal object of this invention is to provide a simple and easily adjustable oscillating mechanism having few parts and which can be economically manufactured. Various other objects of our invention will 30 be obvious, or pointed out hereinafter, reference being made to the accompanying drawings, in which:

Figure 1 is a rear elevation of the fan motor and a vertical cross-section through the oscillating mechanism for said fan.

Fig. 2 is a side elevation of the motor and a vertical cross-section of the oscillating mechanism taken at right angles to Fig. 1.

Fig. 3 is a horizontal cross-section taken 40 approximately on line 3—3 of Fig. 1.

Fig. 4 is a top plan view of the adjusting device.

Fig. 5 is a detail perspective view of the rotary member.

Fig. 6 is a detail perspective view of the adjustable block.

Fig. 7 is a perspective of the casing or cap piece.

Fig. 8 is a detail view of a pivotal member 50 carried by the adjustable block.

Fig. 9 is a vertical cross-section through the adjusting device and showing means for retaining the casing in its adjusted position on the rotary member.

Referring to the drawings, M indicates a 55 motor mounted for rotary movement on a stationary base B and provided with a fan in the usual manner. Carried by said motor is a suitable housing 1 in which is located a reduction gearing 2 operatively connected 60 with the rotor shaft of motor M and having a shaft 4 to which is fixed rotary member 5. The lower face of the rotary member is provided with a transverse groove 5^a designed to accommodate an adjustable block 6 whose 65 shape is such as to permit of its sliding movement longitudinally in groove 5^a across the axis of the rotary member 5. Formed in the adjustable block 6 is a slot 6^a, and fixed to said block is a pin or screw 7. Block 6 is 70 retained in groove 5^a by casing or cap piece 8 having an upwardly extending flange 8^a which is knurled or roughened and surrounds and engages the annular flange 5^b on rotary member 5. The cap piece 8 has an eccentrically located and upwardly projecting pin 8^b which enters and co-operates with slot 6^a in block 6. Cap piece 8 has a curved slot 8^c through which the shank of the pin or screw 7 passes. 75

Screw 7 acts as a pivotal mounting for one end of link 9, the other end of which is pivotally connected to the stationary support on base B. The cap piece 8 is loosely carried by member 5 and is adapted to be manually rotated around said member 5, the annular flange 5^b providing a bearing surface for the inwardly turned edge of the upwardly extending flange 8^a of cap piece 8. 80

The arrangement of pin 8^b on the cap 90 piece, and slot 6^a, in block 6, is such that the rotation of the cap piece in one direction will move block 6 and screw 7 toward the axis of the rotary member and rotation of the cap piece in the opposite direction will cause the 95 block 6 and screw 7 to move away from the axis of the rotary member.

A spring 10 is located in a kerf or slot in the rotary member 5 (see Fig. 9) and presses on the knurled flange of the cap piece and helps to maintain it in its adjusted position. 100

In the operation of our device, the rotary motion of the rotor shaft is transmitted by the reduction gearing to shaft 4 and rotary member 5. The rotary motion of 105 the rotary member will exert pull and thrust moments on the link and will cause the link, pivotally connected to the station-

ary base to move in an arc concentric with the stationary pivot of said link thereby causing the rotary member itself and the motor rotatably mounted in the stationary base and supporting the housing of the rotary member, to oscillate.

To vary the oscillations of the fan, the block is adjusted in the groove of the rotary member so as to move the pivotal connection of link 9 to block 6 toward or away from the axis of the rotary member. When the screw 7 on block 6 is brought in coaxial alinement with the axis of the rotary member, the rotary member no longer exerts any pull and thrust moments on the link and the oscillatory movement of the fan will cease.

In assembling our device, the adjustable block 6 is positioned in the longitudinal groove of the rotary member, and the cap piece is placed in position with the pin carried by said cap piece arranged in the slot in the adjustable block. The edge of the upwardly extending flange is inwardly and downwardly disposed so as to engage the annular flange of the rotary member and thereby hold the cap piece rotatably on the rotary member and retain the adjustable block in the longitudinal groove.

The device when assembled forms a permanent articulated mechanism which is not susceptible of being tampered with and placed out of commission. The block 6 is adjustable in a straight radial movement lengthwise of the slot 5* and the pitman pin carried thereby may be adjusted toward and from the center of the axis of rotation of the block 5. The knurled edge of the rebent housing 8 is preferably formed after the knurling on the housing is made because in this manner the spring can co-operate with the folded edge of the knurled housing, thus avoiding the necessity of any teeth or notches for the spring.

We do not wish to limit ourselves to the device described and illustrated as various modifications may be made and substituted without departing from the spirit of the invention.

What we claim is:

1. In an oscillating mechanism for fans, a rotary member, means for driving the same, an adjustable member carried in the lower end of said rotary member, means pivotally connecting said adjustable member with a stationary support, a housing inclosing the lower end of said rotary member and folded thereover, and adapted to move said adjustable member toward or away from the axis of said rotary member.

2. In an oscillating mechanism for fans, a rotary member having a transverse slot in its lower face, means for rotating said rotary member, an adjustable block located within said slot, a support, a link pivotally

connected to said support and said adjustable block, and an adjusting member engaging said block and adjustably supported on said rotary member by being folded thereover and adapted to move the point of pivotal connection of the link to the block toward or away from the axis of rotation of the rotary member.

3. In a fan, an oscillating mechanism comprising a rotary member, means for rotating said member, an adjustable block located in the under face of said rotary member, a cover plate rotatably carried by the rotary member and folded thereover, and articulated to move said block relative to the axis of the rotary member, and an oscillating link pivotally connected to said block.

4. In a fan, an oscillating mechanism comprising a rotary member having a transverse slot in its lower end, means for rotating same, a support, a movable block located within said slot, a link pivotally connected at one end to said block and at its other end to the support, a flanged casing adjustably mounted on said rotary member by having its flange folded thereon and surrounding the lower end of said rotary member, said casing being in operative engagement with said block and designed to move said block toward and away from the axis of rotation.

5. In a fan, an oscillating mechanism comprising a rotary member, means for rotating the same, a support, a movable member carried by said rotary member, a link having one end pivotally connected to the movable member and the other to said support, a casing inclosing the lower end of said rotary member and adjustably supported thereon, said rotary member engaging said movable member and adapted to move it toward and away from the axis of the rotary member, and means for retaining the casing in its adjusted position.

6. In an oscillating mechanism, a rotating member having a flange at the lower end, a groove in the lower face of said flanged lower end, said groove intersecting the axis of rotation of said flanged rotating member, a sliding block arranged within said groove, a housing rotatively mounted with respect to said flanged rotating member, for holding said block in position, said housing having an opening, a stud passing through said opening and engaging said sliding block, said stud being adapted to connect with an oscillating link.

7. An oscillating mechanism for fans comprising a rotating member having a transversely disposed groove in its underface, a block arranged in said groove and carrying a lug or projection designed to be moved toward or away from the axis of rotation of said rotating member, a housing inclosing

the lower end of said rotating member and mounted thereon, said rotating member having means for engagement with said block whereby the same may be adjusted, said 5 housing having a knurled edge embracing the rotating member, said rotating member having a kerf, and a spring arranged in said kerf and engaging the knurled edge of said housing.

10. S. The combination of a rotating member having a groove intersecting its axis of ro-

tation, a sliding block arranged within said groove and having a transversely disposed slot, a housing arranged on said rotating member and having a lug engaging the slot 15 in said block, said housing having an opening, and a pin or stud on said block projecting through the opening in said housing.

In testimony whereof we hereunto affix our signatures this 5th day of May, 1919.

WILLIAM G. WINTER.
HERBERT I. FINCH.
